UNITED STATES PATENT OFFICE.

ROUGHSEdge WALLWORK AND ARTHUR COLLINGS WELLS, OF MAN-
CHESTER, COUNTY OF LANCASTER, ENGLAND.

ILLUMINATING APPARATUS.

SPECIFICATION forming part of Letters Patent No. 425,154, dated April 8, 1890.

Application filed June 27, 1889. Serial No. 315,754. (No model.) Patented in England September 29, 1888, No. 14,049.

To all whom it may concern:

Be it known that we, ROUGHSEdge WALLWORK and ARTHUR COLLINGS WELLS, subjects of Her Majesty the Queen of Great Britain, residing at Manchester, in the county of 5 Lancaster, Great Britain, (temporarily residing in the city, county, and State of New York,) have invented certain new and useful Improvements in Illuminating Apparatus, and more especially in means for pivotally connecting a burner with a supply-pipe, (for which we have obtained Letters Patent in Great Britain, dated September 29, 1888, No. 14,049;) and we do hereby declare the following to be a full, clear, and exact description of the invention, such as will enable others skilled in the art to which it appertains to make and use the same, reference being had to the accompanying drawings, and to letters 10 of reference marked thereon, which form a part of this specification.

Figure 1 is an elevation of our improved illuminating apparatus. Fig. 2 is a similar view showing the reservoir mounted on 15 wheels. Fig. 3 is a section on line $\alpha\alpha$ of Fig. 1. Figs. 4 and 5 are sectional views of modified constructions of the pivotal connection, and Fig. 6 is an elevation showing the burner-pipe as being portable relatively to a stationary source of illuminant-supply.

This invention has relation to illuminating apparatus, and more particularly to that class which we term "elevated lights," or in which the burner is at such elevation from its support-reservoir as to be beyond reach.

The object of this invention is to provide means whereby ready access may be had to the burner when this becomes necessary from any cause or for lighting the lamp.

The lamp or illuminating apparatus is more especially designed for out-door illumination or for use on board ships or for any other purpose where an elevated light may be desirable; and the invention consists in the swiveling of 40 the supply-pipe to the distributing-main or to said main and to a support for said burner-pipe, so that it may be swung around to bring the burner down within reach.

In the drawings we have shown a construction of illuminating apparatus or lamp of our

own invention; but it will be understood that we do not desire to limit ourselves to the supplying of the illuminating agent to the burner-pipe from the reservoir shown, as the supply-pipe may be connected to any other desired 55 source of illuminant-supply.

A indicates the reservoir for the illuminating agent, which may be liquid or gaseous, though the apparatus is more especially designed for use with a liquid illuminating 60 agent, such as hydrocarbon oil.

B is the supply-pipe, through which the oil is forced by compressing the air in the reservoir, in that the oil is forced into the reservoir and the air therein compressed. Any 65 other desired means may, however, be employed for forcing the oil through the service-pipes.

To the supply-pipe B is swiveled a connecting-pipe C, the swivel-connection being, preferably, of the nature of that shown and described in our application for patent, Serial No. 315,400, filed June 24, 1889, though any other fluid-tight pivotal connection may be adopted. The connecting-pipe C is similarly 75 swiveled to a three-branch union D, into one branch d of which is screwed a stuffing-box gland G, through the axial bore of which extends the end of the connecting-pipe. The branch d' is screwed to a rod R, the foot of 80 which is held in the eye of a bracket or sleeve s, mounted and sliding freely on a standard S, the foot of which rests in a socket a, secured to the reservoir A near its bottom, and said standard passes through a sleeve A' at 85 or near the upper end of said reservoir. Instead of a solid rod R a tube suitably closed at its upper end may be used. The standard S has a bearing s' at its upper end for the key end p of a plug-valve P, screwed into the 90 union D through branch d'. The end p of the valve is angular in cross-section, and the bearing s' on standard S has a like opening to prevent the rotation of the valve in its bearings. The inner end of the valve P is 95 bored or hollowed out, and it has a single port p' communicating with its bore, into which projects the end of the connecting-pipe C. It is obvious that if the set-screw b³ is loosened and the bracket b allowed to slide 100

- off the end of the rod R the said rod and the burner-pipe F, that is connected with the branch d^3 of the union D and that carries the burner H, may be rotated on the plug-valve P to bring the rod and pipe into a horizontal position and simultaneously therewith cut off the supply of oil to the pipe F. In this manner ready access may be had to the burner for lighting it or for any other purpose.
- 10 In Fig. 4 we have shown a slight modification, in which the union D and its pivot are formed of one piece, the pivot or journal d^4 revolving in the bearing s' on the standard. Of course the flow of oil to the pipes will have 15 to be cut off by means of the regulating-valve V or a stop-cock in the supply-pipe if the burner needs attention. By means of these pivotal connections the elevation of the burner may also be regulated.
- 20 In Fig. 5 we have shown the burner-pipe pivoted directly to the supply-pipe, the said burner-pipe being provided with a bearing for the valve-plug, which is screwed into an elbow of the supply-pipe. Although we have 25 shown the supply and burner pipes supported directly from the oil-reservoir, it will be understood that this is not absolutely necessary, as the supply-pipe may be connected with any other desired source of illuminant-supply, 30 and its end and the burner-pipe and its pivot may be supported from any suitable stand or other support.
- If desired, the burner-pipe and a portion of the supply-pipe may be made portable irrespective of the reservoir and connected therewith or with any other suitable source of illuminant-supply by a flexible pipe, as shown 35 in Fig. 5. This arrangement may, for instance, be of advantage on board ship, as the reservoir may be below decks at any desired 40 point and connected with the burner by means of a flexible pipe B', connected with the pipe C, as described, or otherwise.
- When the swivel or pivotal connections between the burner-pipe F and the supply-pipe C and between the latter and the feed-pipe B are such as described in our application for 45 patent hereinabove referred to, the burner and connecting pipes may be readily disconnected from each other and from the supply-pipe by simply unscrewing the gland G. On the other hand, by removing the screw or pin p^2 from the key end p of the valve the burner-pipe may be disconnected from its standard 50 S, and the latter, simply resting in the socket b and passing through the sleeve b', may be readily removed from the apparatus. Finally, the burner-pipe and the retaining-rod may be disconnected from the union-piece, and when 55 the burner-pipe is a long one it may be made in sections, so that the parts can be arranged in a compact form for transportation, the burner being also detachably connected with the burner-pipe.
- 60 Having described our invention, what we claim, and desire to secure by Letters Patent, 65 is—

1. An illuminating apparatus comprising a reservoir for the illuminating agent, a supply-pipe connected with the reservoir, a burner-pipe connected with the supply-pipe and adapted to revolve in a vertical plane on a horizontal axis, and a burner connected with the burner-pipe, said parts being arranged to form a portable illuminating apparatus, as 75 and for the purposes described.

2. An illuminating apparatus comprising a reservoir for the illuminating agent, a supply-pipe connected with the reservoir, a support for said supply-pipe, a burner-pipe connected 80 with the supply-pipe and adapted to revolve in a vertical plane on a horizontal axis, and a burner connected with the burner-pipe, said parts being arranged to form a portable illuminating apparatus, as 85 and for the purposes described.

3. An illuminating apparatus comprising a portable reservoir, a supply-pipe connected therewith, a burner-pipe connected with the supply-pipe and adapted to revolve in a vertical plane on a horizontal axis, and a burner connected with the burner-pipe, said supply 90 and burner pipes being supported from the reservoir, substantially as and for the purposes specified.

4. The combination, with a pipe for supplying an illuminating agent to a burner and the burner-pipe, of the union D, connected with the supply and burner pipes, as set forth, the rod R, screwed into one of the branches 100 of said union, the standard S, carrying the adjustable sleeve s, and the valve-plug P, provided with an axial passage, into which projects the supply-pipe, a passage at right angles thereto, and a squared end fitted into 105 a corresponding bearing in the standard S, substantially as and for the purposes specified.

5. The combination, with the pipe C, the union D, burner-pipe F, and rod R, arranged relatively to one another, substantially as set 110 forth, of the standard S and a horizontal pivot extending into the union D and having its bearings at one end in the standard and at the other on the pipe C, said pipe extending into an axial passage of said pivot, which 115 axial passage merges into a radial passage in communication with the burner-pipe, substantially as and for the purposes specified.

6. An illuminating apparatus comprising a reservoir for the illuminating agent, a supply-pipe, and a standard connected with said reservoir, in combination with a burner-pipe, a horizontal pivot having its bearing at one end on the supply-pipe and at the other in said standard, said burner-pipe being revolvable on or with the horizontal pivot, and a communication between the burner and supply pipes through said pivot, substantially as 125 and for the purposes specified.

7. An illuminating apparatus comprising a 130 reservoir for the illuminating agent, a supply-pipe, and a standard connected with said reservoir, in combination with a burner-pipe provided with an interiorly-screw-threaded

bearing, an exteriorly-screw-threaded plug-valve screwed into said bearing, said valve being supported at one end from the supply-pipe and at the other from the standard as to prevent its rotary motion, and a passage formed in said valve in communication with the supply and burner pipes, substantially as and for the purposes specified.

8. An illuminating apparatus comprising a reservoir for the illuminating agent, a supply-pipe, and a standard connected with said reservoir, in combination with a burner-pipe provided with an interiorly-screw-threaded bearing, an exteriorly-screw-threaded plug-valve screwed into said bearing, said valve

being supported at one end from the supply-pipe and at the other from the standard as to prevent its rotary motion, and a passage formed in said valve in communication with the supply and burner pipes, and means for locking the latter pipe against rotation on the valve-plug, substantially as and for the purposes specified. 20

In testimony whereof we affix our signatures in presence of two witnesses.
